(57) **CLAIM**

The ornamental design for a daily desk calendar, as shown
and described.

DESCRIPTION

FIG. 1 is a perspective view showing a new and ornamental
design for a daily desk calendar;

FIG. 2 is a top plan view thereof;

FIG. 3 is a rear elevation view thereof;

FIG. 4 is a front elevation view thereof;

FIG. 5 is a bottom plan view thereof; and,

FIG. 6 is a side elevation view thereof, the opposite side
being a mirror image.

The broken line showing of book pages in FIGS. 1, 3, 4 and
6 are included for the purpose of illustrating environmental
structure and forms no part of the claimed design. The
broken lines seen on the surface of the claim are understood
to represent stitching.
